INVENTOR:

JAMES V. BROWN.

UNITED STATES PATENT OFFICE.

JAMES V. BROWN, OF DE SOTO, ILLINOIS.

HINGE.

SPECIFICATION forming part of Letters Patent No. 536,125, dated March 19, 1895.

Application filed July 10, 1894. Serial No. 517,047. (No model.)

To all whom it may concern:

Be it known that I, JAMES V. BROWN, a citizen of the United States, residing in De Soto, in the county of Jackson and State of Illinois, 5 have invented a certain new and useful Improvement in Hinges, of which the following is a full, clear, and exact specification.

My invention relates to an improvement in hinges, the object being to provide an article 10 of the character designated which will combine simplicity, durability and strength and which may be manufactured and supplied to the trade at a greatly reduced cost.

To these ends my invention consists in the 15 improved construction and combination of parts, as more fully described and pointed out in the claim.

In the drawings:—Figure 1 is a perspective view of my improved hinge and Fig. 2 is a 20 similar view with the parts separated.

Similar numerals of reference indicate similar parts in both figures of the drawings.

Referring to the drawings, 1, 2 designate the two hinge sections the former carrying 25 two knuckles and the latter one knuckle, as shown in Fig. 2.

Each hinge section is formed of a single blank, which is at a suitable point, as at 3, bent at right angles and then doubled upon 30 itself, as at 4 and thereby bringing the end of the strap, upon which the knuckles of the hinge are formed.

It is obvious that the two sections should be made of opposite form so that the knuckles 35 of the two leaves, will fit together and allow of the passage therethrough of the pintle 5. Suitable holes 6, for the purpose of securing the two right-angled parts of each leaf to the object, by means of screws, are formed in the 40 leaves, as shown in Fig. 2. By this construc-

tion, in forming the hinge blanks, no waste of material need be had, except that which comes from the contour of the fancy parts of the sections, and should these parts be made square no waste whatever will occur, as the 45 blank used for each is the same, excepting that the part cut away in leaf 1, to allow of the entrance of the knuckle on leaf 2, forms the knuckle on leaf 2, and vice versa. It will thus be seen that by forming a die to make the 50 central cut between the two parts of the hinge, when both are cut from a single blank, the part remaining, after one leaf has been cut forms the other leaf.

It is obvious, that by doubling the one part 55 of the leaf gives it added strength and therefore giving it a more substantial form. The advantage derived by forming the knuckles at one end of the hinge, is obvious.

It is not necessary that the two parts of 60 each hinge section should be of the same size, as it is often preferable that the doubled part should be smaller in size than the other part of the hinge section.

Having thus described my invention, what 65 I claim as new is—

A hinge, comprising in its construction, two hinge sections, each of which is formed of a single blank, each blank being bent at right angles and then doubled upon itself, 70 knuckles formed on the ends of the blanks, and a pintle adapted to secure the two hinge sections together, substantially as described.

In testimony whereof I have hereunto set my hand this 14th day of May, 1894.

JAMES V. BROWN.
